UNITED STATES PATENT OFFICE.

HENRY A. LEONHART, OF BANGOR, WISCONSIN.

FURNACE.

Application filed March 31, 1928. Serial No. 266,285.

My present invention has reference to a heating plant, and my object is the provision of a plant for this purpose through which the heat is circulated and radiated in such manner to insure a more constant and uniform delivery thereof than can be obtained by the usual construction of such plants with an equal consumption of fuel.

Another object of the invention is the provision of a heating plant for household use that embodies both the hot air and hot water circulating systems; that may employ either hard or soft coal or wood as a heating agent; in which the products of combustion from the fuel may be caused to circulate through a conduit arranged in the jacket or casing or to be passed directly into the chimney flue as when the fire is first started, and further wherein the gases generated by the fire are controlled in a manner to insure the safety of the plant.

A further object is the provision of a heating plant whose heat conducting ducts or passages may be readily cleaned from the exterior of the jacket or casing, which embodies a grate construction of a simple but extremely novel nature and which is of such arrangement and construction that the same may be readily set up and will require little if any repairs when in practical use.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a side elevation of a heating plant in accordance with my invention, the jacket or casing being in section.

Figure 2 is a sectional view approximately on the line 2—2 of Figure 1.

Figure 3 is a sectional view on the line 3—3 of Figure 2.

Figure 4 is a sectional view approximately on the line 4—4 of Figure 3.

Figure 5 is a sectional view approximately on the line 5—5 of Figure 4.

Figure 6 is a sectional view approximately on the line 6—6 of Figure 3.

Figure 7 is a fragmentary elevation looking toward one side of the furnace to illustrate the rocking mechanism for the grates.

Figure 8 is a fragmentary elevation to illustrate the gas control for the furnace when soft coal is employed for a fuel.

Figure 9 is a sectional view on the line 9—9 of Figure 8.

Figure 10 is an inner face view of a door for the fire box of the furnace to illustrate the damper and the latching means associated therewith.

Figure 11 is a view substantially similar to Figure 10 but showing the latch swung to locking position.

Figure 12 is a sectional view approximately on the line 12—12 of Figure 11.

Figure 13 is a sectional view approximately on the line 13—13 of Figure 3.

Figure 14 is a sectional view approximately on the line 14—14 of Figure 13.

Figure 15 is a sectional view approximately on the line 15—15 of Figure 3.

Figure 16 is a detail sectional view on the line 16—16 of Figure 15.

Figure 17 is a detail sectional view on the line 17—17 of Figure 1.

Figure 18 is a sectional view approximately on the line 18—18 of Figure 17.

Figure 19 is a detail longitudinal sectional view through the heating plant to illustrate the arrangement of one of the grate bars therein.

Figure 20 is a top plan view of one of the grate bars.

Figure 21 is a sectional view approximately on the line 21—21 of Figure 20.

Figure 22 is a sectional view approximately on line 22—22 of Figure 19.

Figure 23 is a sectional view approximately on the line 23—23 of Figure 19.

Figure 24 is a sectional view approximately on line 24—24 of Figure 19.

Figure 25 is a perspective view of the rod or tool employed for removing any one of the grate bars.

In the showing of the drawings the furnace 1 is of a substantially rectangular formation and is arranged in but spaced from a jacket or casing 2. The jacket 2 has an open top that is surrounded and engaged by a depending flange 3 upon a radiator or grate 4. The grate or radiator is let through an opening in the floor 5 of a room above which the

heating plant is arranged. The furnace is divided by a novel construction of grates hereinafter to be described in detail, into a lower ash pit and an upper fire box. On the 5 sides of the furnace there are cast or otherwise secured outwardly directed horizontally disposed substantially rectangular frames 6 and 7, respectively. The outer straight face of the frame 7 is disposed in contact with the outer face of one of the sides of the jacket 2. This side of the jacket is provided with a longitudinal opening 8 which is covered by the outer plate of the frame 6. The frame or casting 6 is formed with a vertically disposed longitudinally extending plate or partition 9 that is, of course, connected to the ends of the frame, and this partition plate 9 is provided with a series of equidistantly spaced round openings 10 that align with similar openings 15 11 in the outer side wall of the furnace 1. These aligning openings are designed to receive therethrough the thickened inner portions 20 12 of the outer bearing members for the grate bars. The thickened portion 12 of each 25 of the bearing members is formed with a peripheral longitudinally extending rib 13, and these tongues are designed to be received in notches 14 in the rounded or headed ends 25 15 of levers 16. The head 15 of each of the levers, is, of course, provided with a bore 30 through which the bearing 12 passes. The bearing member is in the nature of a tube, and the bore thereof is notched, as at 17. Also designed to be received on the bearing members 12 and having notches to receive the ribs 13 thereof are washers 18. These washers contact with the inner face of the partition plate 9, and surrounding each bearing 12 and exerting a tension between the head 40 or hub 15 of the levers 16 and the washer 18 there are coil springs 19. All of the levers 16 are pivotally connected to a bar 20, and by a construction as above described it will be noted that the washers being engaged by the 45 ribs of the bearings and the levers being likewise engaged by the said ribs, the reciprocatory movement of the bar 20 will have no tendency to move the levers out of alignment with each other against the pressure of the springs 19.

The reduced ends of the bearings 12 are indicated for distinction by the numeral 21 and are received through the opening 8 in the outer element of the frame 6 and these ends are also received through rounded openings in plates 22 which are removably secured, preferably through the medium of screws, to the said outer plate of the frame. Surrounding the reduced portion 21 of each of the bearings 12, and exerting a pressure against the plates 22 there are helical springs 23. When it is desired to move any of the bearings 12 it is merely necessary to detach the connecting elements for the plates 22, and thereafter insert the rod 24 (Figure 25) through the

bore of the bearing, and to bring its hooked end 25 into the notch 17, and to exert an outward pull on the rod which will cause the bearing to slide entirely over or partly over the heads 15 of the levers 16 and the washers 18.

The bore of each of the bearings 12 upon its inner end is enlarged and formed with a longitudinally extending rib 26, and this rib is designed to be received in a notch in the 75 rounded or hub ends 27 of the grate bars 28. Each of the grate bars, in a line with its hub 27, is formed with a longitudinal opening 29 therethrough.

The second side of the furnace 1 is provided with round openings in a line with the openings 11, and through these openings there is designed to be passed tubular bearings 30. The inner end of each of the bearings 30 is enlarged or headed, as at 31, to contact with the inner wall of the said side of the furnace. The outer ends of these bearings are received through rounded openings in the outer member of the frame 7. Each of the tubular bearings is formed with a longitudinally extending groove 32 to receive therein ribs which project into the bores of the headed portions 32 of levers 33 and washers 34. A helical spring 35 surrounds each of the bearings 30 and exerts a pressure 45 between the washers 34 and the heads of the levers 33. The headed end 31 of each of the bearings 30 has an enlarged bore formed with a longitudinal groove 36 to receive therein a rib 37 formed on the second hub ends 38 of 100 the grate bars 28.

The grate bars 28 are triangular or substantially V-shaped in cross section and the upper and widened faces thereof are formed with transverse ribs 39 that provide the rest 105 for the fuel. The projecting ends of the ribs 39 in the respective grate bars are, of course, designed to be received between the ribs in the adjacent grate bars.

The levers 33 are each pivotally connected 110 by a bar 40 similar to the bar 20 and the ends of the bars 20 and 40 are received between the outer face of the furnace and the face plate for the said furnace. To these ends of the bars there are pivotally connected depending links 115 41 and 42, respectively. The link 41 is really in the nature of a lever, being projected above its pivotal connection with the bar 20, and to this projecting end of the link or lever 41 there is pivoted another link 43 which in turn is pivoted to the grate rocking lever 44. The link 43, of course, passes through an opening in the casing or jacket 2, and the rocking lever 44 is pivoted between lugs 45 120 on the face plate 46 for the furnace 1. By 125 an arrangement as above described it will be seen that all of the grate bars are simultaneously rocked and that any one of the grate bars may be removed when injured and readily replaced. Access is obtained through the 130

interior of the furnace through an opening that is normally closed by a door 47, and access to the bearing 12 and the parts associated therewith is obtained through an opening in the casing 2. This opening is normally closed by a plate 48, the said plate having a hooked end 49 to engage one of the walls of the opening, and a continuous rib 50 to engage all of the walls of the opening. To lock the plate to close the opening a bolt 51 has its headed end passed through a bridge plate 52, that is a plate that contacts with the inner face of the casing, and which bolt is engaged by a nut 53 arranged on the outer face of the closure plate 48.

Removably secured to one of the inner side walls of a furnace 1, above the grate therein, there is a water jacket or boiler 54, and communicating with this boiler there are water inlet and outlet pipes 55 and 56 which, of course, pass through the side of the fire box and the casing or jacket and the hot water conducting pipe may be connected with suitable radiators whose return or drain pipes may be coupled to the cold water inlet pipe, in the usual manner.

The fuel inlet opening in the furnace is closed by the fuel inlet door 47, hingedly supported upon an angle frame 57 attached to the face plate 6 by screws or bolts 58. The door 47 is provided with a series of openings designed to be covered or uncovered by a slideable plate 59. The inner face of the door 47 has arranged thereon the usual baffle plate 60, and the said inner face of the door has centrally arranged thereon a link 61 to which is attached the shaft of a lever or handle 62. Pivotally secured on the ends of the link 61 there are latching bars 63, respectively that are oppositely directed and that pass through guides 64 on the said inner face of the plate. By swinging the lever the latching elements 63 may be moved to permit of the opening of the door, as disclosed by Figure 10 of the drawings, and by turning the lever in a second direction the link will be moved into longitudinal alignment with the latching elements 62 so that the ends of the said elements will be brought against the inner edges of the frames 57 to hold the door closed. The link is limited in its swinging by contact with a stop element 65 on the said inner face of the door.

The ash pit is also provided with an opening that is controlled by a pivotally supported door 66, the said door being normally latched and being preferably centrally formed with an opening that is closed by the usual swingable auxiliary door 67.

Above the door 47 the face plate and the outer face of the furnace has an additional opening. Of course, the openings for the doors 47 and 67 are disposed in a line with the hollow and substantially rectangular spacing members between the furnace and the

face plate therefor, and the last mentioned opening is arranged in a line with a similar spacing opening. The last mentioned opening is partly covered by a substantially rectangular plate 68 that is removably fixed on the face plate 46. The plate 68 has a central opening 69 therethrough, and bridging this opening there is a connecting element 70. On the outer face of the plate there is a ring enlargement 71 and the said enlargement has oppositely disposed peripheral cam extensions 72, respectively. Guided through a central opening in the part 70 there is a pivot pin 73. Mounted for rotation on this pivot pin there is a damper plate 74. The damper plate 74 has a hub extension 75 that is also journaled on the pivot pin 73 and that is received in a hollow boss 76 from which the pivot pin 73 centrally extends. The boss 76 really provides the hub of an arm or plate 78 that has inwardly extending angle ends 79 that are connected to the face plate 46 for the furnace. The damper plate 74 is in the nature of a disc and is formed with oppositely projecting fingers 80 to ride on the cams 72 when the disc is turned. The disc at the opposite sides of the fingers 80 is formed with angularly extending arms 81 and 82, respectively, and to each of these arms there is connected a flexible element, such as a chain 83 that leads through the radiator plate or grating 4. A pull upon one of the chains will move the damper plate onto the cams to uncover the opening 61 and a pull upon the second element will move the damper plate to bring its fingers 80 off of the cams. A coil spring 84 surrounds the hub of the disc damper 74 and exerts a pressure between the element 76 and the said damper disc. It should here be stated that the damper 74 is only opened when soft coal is being burned in the furnace and is retained open until all of the gases from such fuel is consumed.

The top of the furnace 1 is open and is provided with a continuous groove that is designed to receive therein a continuous rib 85 on the top or crown plate 86 for the said coils. The plate 86 is cast with the upper and longitudinally extending branch 87 of the heat conducting and radiating conduit. This branch 87 has on its under face depending arched ribs 88 that are apertured and that are connected with the sides of the casing for supporting the branch 87 thereon. The top of the branch 87 is formed with closely related spaced longitudinally extending ribs 89 between which the heat from the branch 87 radiates. The conduit branch 87 is preferably rectangular in cross section and has its under face at its outer or free end formed with a projection which is ribbed to be received in the grooves in the outer and vertical branch 90 of the conduit. The branch 90 is formed at one end of the lower horizontal branch 91 of the conduit. Supporting the

branches 90 and 91 at the connecting ends thereof there are leg members 92, and supporting the inner and closed end of the branch 91 there is a substantially rectangular casting 93 that is bolted, as at 94', to one of the sides of the furnace 1. The upper and lower longitudinal or horizontal branches of the conduit are formed, on their outer ends with reduced extensions 94 and 95, respectively which pass through one side of the casing. These extensions 94 and 95 are closed by plates 96, best illustrated in Figures 15 and 16 of the drawings. These plates are substantially similar to the closure plate 48, the said plates having a continuous flange on their inner faces and having a hooked portion 96' to engage with the casing. The plates 96, at the ends thereof opposite the hooks 96' have slotted extensions or lips 97 that receive therethrough slotted plates or bail members 98 connected with the casing 2. Through the members 98 there are passed wedge elements 99 that wedge the lips or projections 97 against the casing. The vertical branch 90 of the conduit is provided with an opening that is surrounded by a spacing element that is received through an opening in the casing. This opening is closed by a cover plate 100 that is removably secured on the casing 2 by bolts 101.

Surrounding an opening in the lower horizontal branch 91 of the conduit and secured to the said branch there is an upwardly directed angularly disposed conduit branch in the nature of a pipe 102. This pipe has an upper angle extension 103 designed to be received in an opening in a chimney breast and the passage through the extension 103 is controlled by a hand operated damper 104. The pipe branch 102 of the conduit, at the junction of the angle branch thereof is formed with an inwardly directed substantially rectangular portion 105. The outer face of this portion 105 has an inwardly directed continuous flange 106 providing the said face of the part 105 with a rectangular opening 107, and surrounding this opening the said face 106 is formed with a continuous groove 108, the said face being thickened in the groove. The groove 108 receives therein a continuous rib 109 that is arranged around a substantially rectangular opening in the outer face or side of the upper horizontal branch 87 of the conduit. The opening 107 is controlled by a pivotally supported damper plate or valve 110, and this valve plate is actuated by a rod 111 that passes through one side of the casing 2. Preferably removably secured on the outlet end 103 of the branch 102 of the conduit there is a laterally extending substantially rectangular plate 112. This plate 112 is bolted or screwed to the inner face of the casing 2, and is provided with a substantially rectangular opening 113. The opening 113 is covered by a closure plate 114 which is

screwed or bolted to the outer face of the casing 2. The plate serves as a support for the outlet end 103 of the conduit, and insures the proper jointure of the branch 87 with the said branch 102 and the removable plate 114 permits of access being obtained to the interior of the casing and to the top of the conduit for the removal or replacing of the damper plate 110.

With a construction as above described, it will be seen that I have produced a heating plant that will take care of practically any grade or quality of fuel. The branches of the combined heat circulating and radiating conduits may be readily cleaned in an easy and convenient manner. The improvement may be employed as a combined hot water heater and hot air heater. Provision is made for gases generated by the fuels used in the furnace, so that such obnoxious gases cannot escape therefrom or injure the occupants of the dwelling in which the plant is installed. The grate is of extremely novel construction and repairs may be made in an easy and convenient manner to any one of the grate bars without interfering with the remainder thereof. When the fire is first started the damper 110 is opened so that the gases and products of combustion will pass directly through the outlet 103. After the fire has burned sufficiently to consume the gases the damper plate 110 is closed so that the heat units will travel entirely through the substantially rectangular conduit before finding an outlet through the chimney. In this manner it will be seen that the entire inner surface of the jacket or casing will be effectively heated and such heat will be directed through the grating or radiator 4. By merely regulating the damper 104 a continuous and even supply of heat at a desired temperature will be directed through the grating or radiator 4. Of course, the water in the boiler 54 will be heated by the fire in the furnace and will circulate through the pipes 55 and 56 in a manner as heretofore described. The boiler 54, upon its upper face is preferably formed with ribs or fins 115 which serve as radiators for the heat units contacting therewith.

Having described the invention, I claim:

1. A heating plant comprising a fire box, a casing surrounding the fire box, and a grating arranged over the open top of the casing, a heat circulating and radiating conduit comprising a substantially U-shaped member made up of connected sections, and the upper branch of the conduit forming the top of the fire box, the lower branch of the conduit having a closed end, supporting means between the lower branch and the fire box of the conduit, legs also supporting the conduit, transversely arranged arched ribs on the under face of the upper branch of the conduit secured to the sides of the casing, longitudinally extending ribs on the top of

said upper branch of the conduit, a pipe member connected to the lower branch of the conduit and having an outlet end extending through the casing, and a damper in said end,
 5 said pipe member having a substantially rectangular box-like portion extending laterally therefrom, and provided with an opening surrounded by a continuous groove, and the upper branch of the conduit having a continuous rib to be received in said groove, and a pivotally supported damper plate for controlling the opening between the said upper branch of the conduit and the pipe member.

2. A heating plant comprising a substantially rectangular fire box having an open top which is grooved, a substantially rectangular casing surrounding the fire box and having one end in close proximity to the fire box, a grating for the open top of the casing, a heat circulating and radiating conduit in the casing, including an outer horizontally disposed branch having a widened end formed with a continuous tongue to be received in the groove of the fire box and its second end formed with an extension which passes through the casing, a flanged plate having a hooked end to engage the inner wall of the extension, wedge means locking the plate on said extension, transversely arranged apertured ribs on the under face of the said branch connected to the sides of the casing, equidistantly spaced longitudinally arranged ribs on the top of the said branch, a substantially L-shaped hollow member having a tongue and groove engagement with the first mentioned branch of the conduit and communicating therewith, a frame-like casting on the closed inner end of the lower branch of the L-shaped member bolted to the fire box, legs supporting the outer end of the said member, both the vertical and horizontal branches of the last mentioned member having extensions which are received through openings in the fire box, flanged plates having hooked ends for closing said openings, latching means arranged exteriorly of the casing for locking said plates, a pipe member connected with the lower branch of the conduit and having an outlet end extending through the casing and a damper in said outlet opening, said pipe member having an opening communicating with the upper branch of the conduit, and a hand operated pivotally supported valve plate for controlling such opening, a boiler in the fire box and inlet and outlet water pipes passing through the casing and connected with the boiler.

35 a substantially L-shaped hollow member having a tongue and groove engagement with the first mentioned branch of the conduit and communicating therewith, a frame-like casting on the closed inner end of the lower branch of the L-shaped member bolted to the fire box, legs supporting the outer end of the said member, both the vertical and horizontal branches of the last mentioned member having extensions which are received through openings in the fire box, flanged plates having hooked ends for closing said openings, latching means arranged exteriorly of the casing for locking said plates, a pipe member connected with the lower branch of the conduit and having an outlet end extending through the casing and a damper in said outlet opening, said pipe member having an opening communicating with the upper branch of the conduit, and a hand operated pivotally supported valve plate for controlling such opening.

40 3. A heating plant comprising a substantially rectangular fire box having an open top which is grooved, a substantially rectangular casing surrounding the fire box and having one end in close proximity to the fire box, a grating for the open top of the casing, a heat circulating and radiating conduit in the casing, including an outer horizontally disposed branch having a widened end formed with a continuous tongue to be received in

the groove of the fire box and its second end formed with an extension which passes through the casing, a flanged plate having a hooked end to engage the inner wall of the extension, wedge means locking the plate on 70 said extension, transversely arranged apertured ribs on the under face of the said branch connected to the sides of the casing, equidistantly spaced longitudinally arranged ribs on the top of the said branch, a substantially L-shaped hollow member having a tongue and groove engagement with the first mentioned branch of the conduit and communicating therewith, a frame-like casting on the closed inner end of the lower branch of the L-shaped member bolted to the fire box, legs supporting the outer end of the said member, both the vertical and horizontal branches of the last mentioned member having extensions which are received through 80 openings in the fire box, flanged plates having hooked ends for closing said openings, latching means arranged exteriorly of the casing for locking said plates, a pipe member connected with the lower branch of the conduit and having an outlet end extending through the casing and a damper in said outlet opening, said pipe member having an opening communicating with the upper branch of the conduit, and a hand operated pivotally supported valve plate for controlling such opening, a boiler in the fire box and inlet and outlet water pipes passing through the casing and connected with the boiler.

45 4. A heating plant comprising a substantially rectangular fire box having an open top which is grooved, a substantially rectangular casing surrounding the fire box and having one end in close proximity to the fire box, a grating for the open top of the casing, a heat circulating and radiating conduit in the casing, including an outer horizontally disposed branch having a widened end formed with a continuous tongue to be received in the groove of the fire box and its second end formed with an extension which passes through the casing, a flanged plate having a hooked end to engage the inner wall of the extension, wedge means locking the plate on 100 said extension, transversely arranged apertured ribs on the under face of the said branch connected to the sides of the casing, equidistantly spaced longitudinally arranged ribs on the top of the said branch, a substantially L-shaped hollow member having a tongue and groove engagement with the first mentioned branch of the conduit and communicating therewith, a frame-like casting on the closed inner end of the lower branch of the L-shaped member bolted to the fire box, legs supporting the outer end of the said member, both the vertical and horizontal branches of the last mentioned member having extensions which are received through 105 openings in the fire box, flanged plates having hooked ends for closing said openings, latching means arranged exteriorly of the casing for locking said plates, a pipe member connected with the lower branch of the conduit and having an outlet end extending through the casing and a damper in said outlet opening, said pipe member having an opening communicating with the upper branch of the conduit, and a hand operated pivotally supported valve plate for controlling such opening, a boiler in the fire box and inlet and outlet water pipes passing through the casing and connected with the boiler.

50 5. A heating plant comprising a substantially rectangular fire box having an open top which is grooved, a substantially rectangular casing surrounding the fire box and having one end in close proximity to the fire box, a grating for the open top of the casing, a heat circulating and radiating conduit in the casing, including an outer horizontally disposed branch having a widened end formed with a continuous tongue to be received in

for closing said openings, latching means arranged exteriorly of the casing, for locking said plates, a pipe member connected with the lower branch of the conduit and having an outlet end extending through the casing and a damper in said outlet opening, said pipe member having an opening communicating with the upper branch of the conduit, and a hand

operated pivotally supported valve plate for controlling such opening, a boiler in the fire box, and inlet and outlet water pipes passing through the casing and connected with the boiler, said boiler having spaced ribs on the top thereof. ¹⁰

In testimony whereof I affix my signature.
HENRY A. LEONHART.
